WINDING DEVICE FOR CINEMATOGRAPH FILMS AND OTHER APPLICATIONS

André Marie Bernard Charlin, Montrouge, France

Application September 17, 1945, Serial No. 616,881
In France April 9, 1945

3 Claims. (Cl. 242—55)

1

It is known that in a cinematograph film projector, the film, after having passed in the projection mechanism, must be wound in a magazine box designed for this purpose.

Since the winding speed varies uniformly from the start when the reel is empty, until the end when the reel is full, it is not possible to have the spindle of the winder driven direct by a gear coupled to the mechanism, but it is necessary to pass through the intermediary of a friction coupling which slips constantly so that the speed of winding shall be compatible with the speed of arrival of the film to the reel.

It is very difficult to construct a friction coupling which permits of obtaining a uniform tension in the film which is being wound. According as the friction is more or less slippery, according to its temperature, to the weight of the film on the reel, fairly considerable variations in the torque are obtained which prejudice the correct winding and even sometimes entail the risk of straining the film which may at times be pulled too violently, which causes the risk of deteriorating its perforations restrained by the unreeler of the projector.

To remedy this state of things, a friction system has been created in which the weight of the reel by constantly increasing renders the torque proportional to the speed. This device essentially constituted by a hub of fairly great diameter lined with a suitable rubbing surface, rotates at constant speed corresponding to the greatest speed the reel should have at the beginning of the winding on. On said hub a reel is mounted which is driven simply by friction by the hub, the friction being greater in proportion as the weight of the film is itself greater. This device gives good results on conditions that at the start the weight is sufficient to ensure a good drive, the reel being empty. Unfortunately, by increasing the weight of the carcass of the reel to obtain this good drive, the moment of inertia of the reel is increased at the same time, so that at the start here may form a loose loop of the film owing to the rapid get-away of the projector and to delay in the acceleration of the reel. The reel then assumes a more and more rapid acceleration and resorbs said loop in a more or less brutal manner, which again entails the risk of damaging the perforations.

This disadvantage can evidently be contended with by making a lighter reel, but by adding at the start a sufficient friction effect to obtain a correct drive; however, the disadvantages and

2

difficulties of manufacturing mechanical frictions are again encountered.

The present invention remedies these disadvantages by creating a winding device in which the winder arm is provided at its driving end with a hub containing a magnet, as well as with an imperatively driven disk against which is placed a sheet of material having a low coefficient of friction, then the reel presents at its centre a sheet metal dome cover intended to cap said hub, in such a manner that the bottom of said dome cover may remain spaced from the end of the magnet of the hub, while its peripheric flange is pressed onto the sheet of material having a low coefficient of friction applied on the disk of the hub by the magnetic attraction of the magnet of the hub on the dome cover of the reel, said magnetic friction coupling being combined with the increase in the friction produced by the increase in the load of the reel in proportion with the winding on of the film. An excellent get away is thus obtained of the very light weight empty reel which is driven by the friction coupling tightened under the action of the magnet, then the friction is next increased as a function of the increase of the load due to the winding on of the film, so that the driving torque is ensured throughout the functioning under optimum conditions.

30 The invention moreover extends to various other characteristics which appear in the detailed description which follows.

A form of embodiment of the winding device conformable to the invention is represented, as 35 an example, in the attached drawing.

Figure 1 is a longitudinal section of the winding device without the reel.

Figure 2 is the side elevation of the reel.

Figure 3 is a cross section of the reel.

40 Figure 4 represents the reel of Figure 3 placed on the left portion of Figure 1.

1 represents the spindle of the winder and 2 the pulley driven at constant speed by the projection mechanism by means of belt 3.

45 Spindle 1 rotates freely in bearings 4 and 5. A steel hub body 6 is pinned to the end of spindle 1. A mild steel disk 8 and a hub 9 of material correctly selected to have a low coefficient of friction and non-magnetic qualities are secured 50 by means of screws 7 to said hub. The latter may, for instance, be made of metal having a low coefficient of friction, Bakelite or fibre.

A magnet 10, presenting a magnetic pole at either end of its axis, is housed and held against 55 axial movement in said hub 9. Said magnet can

advantageously be constituted by a small cylinder of nickel and aluminium base steel, said alloy presenting a great coercive force.

The reel utilized on the winder of Figure 1 comprises a steel hub 11, constituted by a dome cover of stamped mild steel sheet and the outer edge of which is riveted on a disk 12 very light and very even, which may be constituted by a plate of duralumin, sheet metal or even compressed material, fibre, wood, etc.

An aluminium dome cover 13, riveted on hub 11 and centred by the flange of the hub forms the core on which the film 14 is wound. Said dome cover comprises parts or members, such as springs, slits, etc., permitting the hooking on of the end of the film. Holes are provided in said dome cover so as to be able to introduce the fingers to seize the reel full or empty.

In Figure 4 it is noticed that dome cover 11 exactly caps hub 9 and that the bottom of dome cover 11 is opposite magnet 10. There exists between the bottom of the dome cover and said magnet a slight air-gap which depends on the thickness of a sheet or plate 15 made of a non-magnetic substance having a low coefficient of friction the thickness of which is selected so that the magnetic field developed by the magnet and circulating according to the dotted line through steel dome cap 11, steel plate 8 and the steel hub 6 may be sufficiently powerful to determine at the start a sufficiently strong friction on the sheet or plate 15, in order to ensure a correct get-away of the reel at the moment of the starting up of the projector.

It is conceived that this get-away will be excellent since the moment of inertia of the reel, owing to its construction, is extremely reduced. In proportion as the film is wound onto core 13, its weight increases more and more, determining an increasingly greater force of friction between the steel dome cover 11 and the non-magnetic hub 9, which thus ensures, by a correct calculation of the ratio of the diameters, a constant tension in the film by the unreeeler of the projector.

The winding device of the invention presents various other advantages. It facilitates the putting in place of the reel and its removal by the disappearance of the locking and of the driving dog, which are replaced by the magnetic field. On the other hand, the arrangement lends itself readily to an accurate construction, nevertheless very robust, which permits of ensuring a perfect truing of the members in rotation and consequently an excellent winding on of the film, without the latter running the risk of rubbing unnecessarily against the edge of the reel as often happens in the usual arrangements.

By selecting correctly the materials with a low coefficient of friction of the hub 9 and of the plate 15, it is even possible not to provide any lubrication of the rubbing surfaces, which considerably simplifies maintenance. This winding device may be utilized not only for the normal 35 mm. film, but also for any other size.

It might likewise be utilized for the spooling

of any substance other than film. For instance, it might be employed with the same advantage in the automatic machines for printing photographic prints on paper or the winding of delicate fabrics, such as silk or others and, in a general manner, wherever it is desired to wind any sort of strip presenting a certain fragility as the case happens in cinematography.

Various modifications might moreover be made in the example of embodiment described without exceeding the scope of the invention. In particular, the reel might be constituted in a different manner. Likewise, the magnet might be arranged in any suitable way in the hub fixed to the end of the driving spindle.

I claim:

1. A winding device for cinematographic films comprising a winding shaft, bearings supporting said shaft, driving means at one end of said shaft, 20 a hub support fixed at the other end of said shaft, a disk made of magnetic material and a hub made of non-magnetic material having a low coefficient of friction fixed on said hub support, a plate made of non-magnetic material having a low coefficient of friction applied on said disk, a magnet presenting a magnetic pole at either end of its axis housed inside said hub, a dome-shaped reel hub having a peripheral flange and being disposed on the hub of said shaft in such a manner that the bottom of said reel hub is maintained in spaced relation from the end of said magnet while said flange is forced against said plate by the magnetic attraction of said magnet on said reel hub, a disk secured to the outer edge of said flange, a reel body fixed on said reel hub, and means on said reel body for securing the end of the film to be wound on.

2. A winding device for cinematographic films according to claim 1, said hub support including 40 a machined portion and a flange behind said portion, said plate comprising a washer, said hub made of non-magnetic material being supported on said portion, and means securing together said latter-mentioned hub, said washer and said disk to said latter-mentioned flange.

3. A winding device for cinematographic films according to claim 1, said reel body being cylindrical in shape, including means securing together 50 said reel body and said reel hub, and said reel body being provided with openings to facilitate handling thereof.
